UNITED STATES PATENT OFFICE.

JOHN F. LEWIS AND JOHN LLOYD, OF NORTH BRADDOCK, PENNSLYVANIA.

TRACK-RAIL.

1,175,648.

Specification of Letters Patent. Patented Mar. 14, 1916.

Application filed December 24, 1915. Serial No. 68,572.

To all whom it may concern:

Be it known that we, JOHN F. LEWIS and JOHN LLOYD, both citizens of the United States, and residing at North Braddock, in the county of Allegheny and State of Pennsylvania, have invented certain new and useful Improvements in Track-Rails, of which the following is a specification.

Our invention relates to the construction of the rails forming the tracks of steam, electric and like railways; and the invention, which is applicable to the T-rails usually employed on steam railroad systems and to the girder rails and guard rails of street railway systems, more particularly relates to the construction of the rails forming the curved tracks where the wear on the side of the rail head is excessive and the life of the rail is short, due to the excessive wear.

One object of our invention is to provide a track rail of improved construction having novel means whereby friction between the rails and the flanges on the wheels of the cars, locomotives, and other rolling stock is lessened, wear on the rail heads is very materially reduced, and liability of derailment on curved tracks of the railway is avoided and overcome.

Another object of the invention is to provide a track rail having novel means for supplying and maintaining a supply of lubricant for the wheel flanges of the rolling stock.

A further object of the invention is the provision of a track rail having the novel construction and arrangements of parts shown in the drawings, and covered by the claims, and more fully described herein-after.

Referring now to the drawings, forming part of this specification, Figure 1 is an end elevation of a rail of the T-head type, the rail head being partly broken away to show one form of lubricant retaining pocket or recess of rails made in accordance with our invention. Fig. 2 is a side elevation showing a portion of the length of the rail of Fig. 1. Fig. 3 is an end elevation of a guard rail, of the girder type, used on street railways, having lubricant holding pockets in the side surfaces of the head and guard flange, the rail being partly in section to show the construction of a modified form of lubricant pocket or recess. Fig. 4 is a side elevation of a portion of the length of the rail of Fig. 3, the guard flange being partly

broken away to show the relative arrangement of the multiplicity of pockets. Fig. 5 is an end elevation of the head portion of a girder guard rail, partly in section, to show a modified form of lubricant holding pocket. Fig. 6 is a side elevation, with the guard flange partly broken away, of a part of the length of the rail of Fig. 5. Fig. 7 is an end elevation, similar to Fig. 1, and Fig. 8 is a side elevation like Fig. 2, showing another modification in the shape of the lubricant retaining pockets in rails constructed in accordance with our invention. Fig. 9 is an end elevation, and Fig. 10 is a side elevation similar to Figs. 1 and 2, showing another form of lubricant holding pocket. Fig. 11 is an end elevation, and Fig. 12 is a side elevation similar to Figs. 1 and 2, showing still another form of lubricant holding pocket or recess. Fig. 13 is an end elevation, and Fig. 14 is a side elevation, like that of Figs. 1 and 2, showing a still further modification in the construction of the lubricant containing pocket of rails made in accordance with our invention.

In the accompanying drawings the numeral 2 designates the head of the rails which is joined integrally by the web 3 to the base flange 4 of the rails.

In the construction shown in Figs. 1 and 2, the side surface 25 of the rail head 2 is provided with a series of recesses or indentations 26 which are rectangular in outline and which are arranged in rows, with the rows of depressions in staggered relation. The recesses preferably are formed in the rail rolling operations, in such case suitably shaped projections being provided on the roll surfaces to form the recesses or indentations on the side of the rail head during the rail rolling operations. However, when desired or found necessary, the recesses may be formed by milling, by drilling, or in any other desired manner, after the rails have been rolled, and even after the rails have been placed in position on the road bed of a railway track.

In the construction shown in Figs. 3 and 4, the side surface 45 of the rail head 2 is provided with a multiplicity of staggered recesses 46 which are cylindrical in outline, and one side surface 47 of the guard flange 5 of this rail, which is of the girder type used in street railway constructions, is provided with a similar series of recesses 46.

In the construction shown in Figs. 5 and

6, the side surface 65 of the rail head 2 is provided with a series of narrow recesses 66 arranged to extend lengthwise vertically. As the rail of Figs. 3 and 4 is of the guard 5 rail girder type, the side surface of the guard flange 5 is also provided with a series of recesses 66 similar to those in the side 65 of the rail head.

In the construction shown by Figs. 7 and 10 8, the side surface 85 of the rail head 2 is provided with a zigzag groove or recess 86 which extends from one end to the other of the rail or which may extend only through such portions of the length of the rail as is 15 deemed necessary or desirable. When desired, the recess 86 may be straight instead of, as is shown in these figures, being made zigzag, in form.

In the construction shown in Figs. 9 and 20 10, the side surface 105 of the rail head 2 is provided with a series of spaced recesses 106 which are cylindrical in outline.

In the construction of Figs. 11 and 12, the side surface 125 of the rail head 2 is 25 provided with a series of narrow recesses 126 arranged to extend lengthwise vertically at separated points in the length of the rail.

In the construction shown in Figs. 13 and 14, the side surface 145 of the rail head 2 is 30 provided with a series of narrow recesses 146 which extend lengthwise at an angle to the horizontal.

After the rails having the recesses or indentations in the side surfaces of the rail 35 heads 2 are placed in position in a railway track, the pockets forming the recesses are filled with a viscous lubricant such as grease or tallow, or they may be filled with lead or other soft metal, graphite or other semi-fluid lubricant or lubricating compound.

The side surface of the rail having the 40 pockets, being on the side of the rail engaging with the wheel flanges of rolling stock hauled on the track, will be smeared with lubricant from the pockets, and in this way will greatly lessen the friction between the rails and the wheel flanges of the rolling stock.

When found necessary or desirable, the 45 pockets formed by the recesses in the side surfaces of the rail heads 2 are filled with waste, felt, or similar absorbent material, and the waste is impregnated or saturated with oil or other liquid lubricant. In such 50 case the waste within the pockets will ab-

sorb the liquid lubricant and maintain a supply of lubricant for an indefinite time in position to be transferred to the passing wheel flanges and be transferred by the wheel flanges to the side surfaces of the rail heads 60 coming in contact with the wheel flanges.

The advantages of our invention, which will be clearly apparent to those skilled in the art, arise from the provision and maintenance of a supply of lubricant, in position 65 to come into contact with the wheel flanges of rolling stock hauled over the rails, and in position to be transferred through the medium of wheel flanges to the side surfaces of the rails engaged by the wheel flanges. 70 In this way the enormous friction between the wheel flanges and rail heads, especially on the curved tracks of railways, is greatly lessened and the extremely rapid wear on the side surfaces of the rail heads on curved 75 tracks is materially reduced.

Modifications in the construction and arrangement, and the location of the lubricant containing pockets, may be made without departing from our invention as defined in the 80 appended claims.

We claim:

1. A railway track rail having a car wheel supporting head, with at least one side of said head having a recess therein forming a 85 lubricant receiving pocket, and said pocket being adapted to maintain a supply of lubricant in position to contact with and lubricate the flanges of car wheels traveling on said track rail.

2. A railway track rail having a car wheel supporting head, and the wheel flange engaging side of said head having a plurality of recesses therein, said recesses forming lubricant receiving pockets adapted to maintain a supply of lubricant in position to contact with and lubricate the flanges of car wheels traveling on said track rail.

3. A railway track rail having a car wheel supporting head and a guard flange, the adjacent sides of said head and guard flange having recesses therein and said recesses forming lubricant receiving pockets adapted to maintain a supply of lubricant in position to contact with and lubricate the flanges of car wheels traveling on said track rail.

In testimony whereof we have hereunto set our hands.

JOHN F. LEWIS.
JOHN LLOYD.
